UNITED STATES PATENT OFFICE.

CURTIS E. BATCHELOR, OF OKLAHOMA CITY, OKLAHOMA.

DESIGN FOR A DOLL.

Application filed June 10, 1927. Serial No. 22,386. Term of patent 7 years.

To all whom it may concern:

Be it known that I, CURTIS E. BATCHELOR, a citizen of the United States of America, residing at Oklahoma City, in the county of Oklahoma and State of Oklahoma, have invented a new, original, and ornamental Design for a Doll, of which the following is a specification, reference being had to the accompanying drawings, forming a part thereof.

I claim:

The ornamental design for a doll as shown.

CURTIS E. BATCHELOR.
